US0D1014766S

(12) United States Design Patent (10) Patent No.: US D1,014,766 S
(45) Date of Patent: * Feb. 13, 2024

(54) MASSAGE PILLOW

(71) Applicant: ZiCheng Zheng, Shenzhen (CN)

(72) Inventor: ZiCheng Zheng, Shenzhen (CN)

() Term: 15 Years

(21) Appl. No.: 29/800,583

(22) Filed: Jul. 22, 2021

(51) LOC (14) Cl. 24-01

(52) U.S. Cl.

USPC D24/200; D24/215

(58) Field of Classification Search
